UNITED STATES PATENT OFFICE.

DAVID FICKES AND MERL FICKES, OF JEROMESVILLE, OHIO.

ROAD DRAG OR SCRAPER.

Application filed November 17, 1924. Serial No. 750,389.

To all whom it may concern:

Be it known that we, DAVID FICKES and MERL FICKES, citizens of the United States, residing at Jeromesville, in the county of 5 Ashland and State of Ohio, have invented new and useful Improvements in Road Drags or Scrapers, of which the following is a specification.

This invention relates to road working 10 apparatus and has for its object the provision of a novel road drag or scraper whereby the surface of a road may be effectually scraped and recrowned from time to time so as to insure proper drainage in wet 15 weather.

An important object is the provision of a 20 device of this character which embodies adjustably mounted scraper blades equipped with means for holding them in any desired 25 adjusted position, the device being furthermore so arranged that either blade may be thrown into active service so that the device is what may be called reversible for use at either side of a roadway.

Another object is the provision of a device 30 of this character which is equipped with trailer chains which will operate to level off the surface of loose earth scraped up by the blades.

Yet another object is the provision of a 35 device of this character which will be substantially free from side draft and which will therefore be easy to pull along without the expenditure of a great deal of labor and without any necessity of employing a large number of draft-animals or the like.

An additional object is the provision of a 40 device of this character which will be simple and inexpensive in manufacture, easy to adjust, positive in action, efficient and durable in service, and a general improvement in the art.

With the above and other objects and advantages in view, the invention consists in 45 the details of construction to be herein-after more fully described and claimed, and illustrated in the accompanying drawings in which:

Figure 1 is a plan view of the device.

Figure 2 is a side elevation, and

Figure 3 is a cross section on the line 3—3 of Figure 1.

Figure 4 is a detailed sectional view illustrating the type of pivot used.

Referring more particularly to the draw

ings, the numeral 10 designates a plate or platform member on the underside of which is secured, as for example, by means of rivets 11 or the like, forwardly extending spaced parallel bar members 12 at the forward ends of which is secured a cross bar 13. Secured to the cross bar 13 at the point 14 where connection is made with the forwardly extending bar 12 are rearwardly diverging brace bars 15 which are secured to each other as shown at 16 and which carry a rear cross bar 17. It should be stated that near its rear edge the member 10 is provided with an upstanding flange 18 for a purpose to be described.

In connection with the stationary frame above described, I make use of a pair of scraper blades 19 and 20, which are similar and which are located at opposite sides of the frame above described. These scraper 75 members carry upstanding forked brackets 21 and 22 pivotally connected, respectively, with the cross bars 17 and 13. By this mounting it will be seen that the scrapers are capable of swinging movement with respect to the stationary frame. At the forward ends of the members 19 and 20 are clevises 23 connected by a draft chain 24 to which is connectable, at any desired point, a draft ring 25 or the like to which power 80 may be applied for pulling the device along a road. Connected with the rear ends of the members 19 and 20 are other brackets or clevises 26 with which are connected chains 27 which trail along behind the device and which are for the purpose of leveling off loose ground scraped up by the 85 blades.

Extending longitudinally of the members 90 19 and 20 and secured upon the outer sides thereof, are bars 28 which are preferably of angle iron construction and to which are secured upstanding elongated slotted members 29 pivoted at 30 upon the outer end portions of the upstanding flange 18 as shown 95 in Figure 3. Pivotally connected at 31 with the flange 18 are outwardly inclined upwardly extending levers 32 slidably engaged through the elongated slotted members 29 and formed with a plurality of holes 33 through any one of which may pass a securing pin 34 passing through a suitable hole in each of the upstanding lever members 29. In the use of the device, it is intended that 100 one of the blade members should travel in a 105 110

straight ahead direction along the side of the road and that the other should be inclined with respect to the road and be adjusted by means of its lever so as to be inclined with respect to the surface travelled over and to exert a scraping action upon the earth. The blade which travels at the side of the road is left in vertical position so as to act as a guide for the device while the inclined blade acts to scrape up the ground and move it along so as to fill all hollows and depressions and make the necessary crown for insuring proper drainage during wet weather. Owing to the peculiar arrangement of the parts it is obvious that there will be no side draft and that the device will be consequently extremely easy to pull along. Owing to the fewness of the parts it is evident that there is very little to get out of order and owing to the adjustability of the two blades it is obvious that either may be used as a guide and the other as the scraper simply by changing the line of pull or the point of connection of the draft connection with the chain 24. In this way it is evident that the device may be easily reversed for use when working upon either side of the roadway. Owing to the ruggedness of the construction it is evident that there is very little to get out of order so

that the device should have a long and satisfactory life.

While we have shown and described the preferred embodiment of the invention, it should be understood that we reserve the right to make such changes in the form, construction and arrangement of parts as will not depart from the spirit of the invention or the scope of the subjoined claim.

Having thus described the invention, we claim:

In a road scraper, a stationary frame including a platform, forwardly extending bars connected therewith, a forward cross bar connected with said forwardly extending bars, diagonally extending cross bars secured in crossed relation and secured to said forward cross bar, a rear cross bar connected with the rear ends of said diagonal bars, scraper blades pivotally mounted on the ends of said forward and rear cross bars, elongated upstanding members carried by said scraper blades and levers pivotally mounted upon said platform, slideable through said elongated members and pivotally adjustably connected with the latter.

In testimony whereof we affix our signatures.

DAVID FICKES.
MERL FICKES.
